FOLDING TABLE AND CHAIR COMBINATION

Catherine B. Creveling and Elmer V. Pennell,
Patterson, N.Y.

Filed Apr. 3, 1962, Ser. No. 184,728
7 Claims. (Cl. 297—140)

The invention here disclosed relates to a combination of foldable table, convertible for use either as a low coffee table or as a full height, full size dining table, with matching foldable chairs, adapted to be housed when not in use within the table structure and readily accessible and quickly removable and set up when required for use with the table.

Objects of the invention have been to provide such a combination in a truly practical desirable form and all at a reasonable cost.

Other special objects of the invention have been to provide both the table and chair structures in attractive form, desirable as such articles of furniture.

Other objects of the invention and the novel features of construction, combination and relation of parts through which the objects are attained are set forth and will appear in the course of the following specification.

The drawings accompanying and forming part of the specification are illustrative of a present practical embodiment of the invention.

Structure however may be modified and changed as regards the immediate illustration, all within the true intent and scope of the invention as hereinafter defined and claimed.

FIG. 1 in the drawings is a side elevation of the table in lowered position with the leaves dropped to conceal internal parts.

FIG. 2 is a similar view with the front leaf removed to expose operating parts.

FIG. 3 is a side elevation showing the table raised and the leaves lifted.

FIG. 4 is an end elevation showing the table in the lowered position with the leaves dropped as in FIG. 1.

FIG. 5 is an end view similar to FIG. 4 showing the table raised and leaves lifted.

FIG. 6 is a bottom plan view of the table with parts in the lowered position as in FIG. 2.

FIG. 7 is a broken part sectional enlarged detail illustrating particularly the slide and operating connections by which the table is locked in either the lowered or raised position.

FIG. 8 is a broken sectional detail on substantially the plane of line 8—8 of FIG. 7.

FIG. 9 is a broken end elevation and diagrammatic view showing parts of the table raising and lowering mechanism with connections for lifting and lowering one of the leaves.

FIG. 10 is an end elevation similar to FIG. 4 but showing how the folded chairs are stowed in supporting racks within the body of the table.

FIG. 11 is a broken sectional view on substantially the plane of line 11—11 of FIG. 10, showing how four folded chairs can be stacked within the table structure.

FIG. 12 is a side elevation of one of the folding chairs in the set up condition.

FIG. 13 is a front elevation of the same.

FIGS. 14 and 15 are side and bottom views respectively of the flat folded chair.

The table is shown as made up essentially of a top 20 to which drop leaves 21, 22 are hinged and two pairs of aligned crossed legs 23, 24 pivoted in scissors fashion on a rod 25, FIG. 5, also utilized as a spacer between the two pairs of legs.

The upper ends of the crossed legs are connected in

2

spaced relation by rods 26, 27 sliding in guideways 28, 29 attached to the underside of the table top.

The pivot rod 25 slides in the vertical guideway 30 provided between the pair of spaced frames 31, 32 dependent from the table top.

The lower ends of the crossed legs may be equipped with rollers, wheels or castors 33 which, in addition to promoting mobility, facilitates spreading and collapsing movement of the legs as the table is lowered or raised.

10 Springs 34, 35 connected between the top rods 26, 27 and the frames 31, 32, FIGS. 2 and 3, draw the upper ends of the scissor legs together to aid in raising the table from the lower FIG. 2 position to the raised FIG. 3 position.

15 The table is locked in either lowered or raised position by plates 36, FIG. 7, slotted at 37 to slide over guide pins 38 on frame 32 into position above or below the cross rod 25 to hold the legs in the table lowered position, FIG. 2, or the lifted position, shown in FIG. 7.

20 The locking plates 36 are released by a cross bar handle 39 carried by levers 40 pivoted at 41 and pivotally connected at 42 with links 43 which in turn are pivotally connected at 44 with elbow links 45 attached to the locking plates 36 intermediate their ends and slidably pivoted at 46 at their upper ends.

25 Springs 47 attached to links 43 normally hold these parts in the locking position shown in FIG. 7 with the locking plates 36 obstructing the vertical guideway 30 and positioned either above or below the cross rod 25.

30 The leaves of the table are automatically swung up and down in the table lifting and lowering operations by linkage, illustrated in FIG. 9 as comprising levers 48 pivoted at 49, carrying pads 50 at their upper outer ends slidably engaging the undersides of the leaves and pivoted at their lower ends at 51 to drag links 52 pivoted at 53 on the cross rod 25.

35 The broken lines in FIG. 9 show how when the table is lowered the lever 48 will be rocked by link 52 to lower the leaf which it supports to the lowered position.

40 The construction disclosed provides space beneath the top and between the crossed legs for storage of the chairs used with the table.

45 This is shown in FIGS. 10 and 11 which illustrate double tiered inclined racks 54, 55 positioned to slidably receive the folded chairs illustrated at 56.

50 These chairs are made up to fold into the compact flat folded relation shown in FIGS. 14, 15 by constructing them with pivotally connected crossed front and back legs 57, 58, FIG. 12 with backs 59 pivotally connected at 60 with the upper ends of the front legs 57 and seats 61 pivotally connected at 62 with the upper ends of the back legs 58 and pivoted at 70 to the lower portion of the back 59.

55 Yokes 63 pivoted at 64 near the upper ends of the front legs 57 serve to secure the chairs in the open or folded positions by dropping into notches 65, 66 in a bar 67 on the underside of the seat.

60 Springs 68 hooked over the latch bar 67 and attached to the pivotal support 69 of the yoke urge the pivotally connected chair parts into the upstanding relation shown in FIG. 12.

65 In the flat folded condition shown in FIGS. 14, 15 the chairs can readily be stacked in the relation shown in FIGS. 10 and 11 concealed from view by the dropped leaves.

70 If desired the enclosure may be further completed by panels at the ends of the table which may be hinged to the table top and be ornamented to appear as drawers or other ornamental features.

75 The complete organization, the table with enclosed folded chairs and the table alone and the chairs used

with the table are ornamental and attractive in appearance and entirely practical for the purposes intended.

The table is safely locked in either the lowered or raised position but can be quickly converted from a coffee table to a dining table simply by operating the release handle 39 and applying slight lifting or lowering force to the table top, the counterbalance springs 34, 35 assisting in such operations.

In converting to the dining table the leaves are automatically raised, providing a table of full size.

The chair racks 54, 55 are sloped downwardly from the opposite ends of the table, thus to nest and hold the folded chairs against shifting when the table is moved from one place to another.

The table construction provides ample storage space 15 for the flat folded chairs illustrated.

The racks for this purpose may or may not be used. FIGS. 2 to 9 show the table without the racks and FIGS. 10 and 11 show the same table with racks installed.

What is claimed is:

1. Folding table and chair combination comprising the combination of table top having hinged drop leaves, pairs of aligned crossed legs, a pivot rod spacing the pairs of crossed legs and pivotally connecting the legs of each pair, the upper ends of opposed legs being connected in spaced relation by cross rods, guides on the under side of the table top slidably receiving said cross rods for movement parallel to said table top, upright guides dependent from the table top slidably receiving said pivot rod for movement perpendicular to said table top whereby said legs are constrained to move in unison, a hand releasable lock for securing said pivot rod against movement in said upright guides and a rack dependent from the table top for storing chairs in folded position beneath said top and covered by said leaves in lowered position. 35

2. The invention according to claim 1 with means for automatically lowering the drop leaves when the table is lowered and for automatically lifting said leaves when the table is raised.

3. The invention according to claim 1 in which said 40 rack is accessible at the end of the table between the leaves, and flat folding chairs of a size to enter said rack at the end of the table.

4. A table for use as a low coffee table or a high dining table comprising a table top having hinged drop leaves, 45 aligned pairs of crossed legs, a pivot rod spacing the pairs

of crossed legs and pivotally connecting the legs of each pair, upright guides dependent from the table top and slidably receiving said rod, cross rods connecting the upper ends of the crossed legs, guides on the underside of the table top slidably receiving said cross rods and a hand releasable lock beneath the table top for securing said pivot rod in said upright guides in position with the table top lowered as a coffee table or raised as a dining table.

5. The invention according to claim 4 in which said releasable lock comprises obstructing means normally extending into said upright guides, said pivot rod being slidably into position above or below said obstructing means.

6. The invention according to claim 4 with racks beneath said table top and folding chairs nested in said racks, said chairs having pivotally connected crossed front and back legs, backs pivotally connected to the upper ends of the front legs and seat pivotally connected to the upper 20 ends of the front legs and to said backs to thereby fold into flat condition for entry in said racks.

7. A table according to claim 4, further comprising: a set of wheels mounted at the lower free end portions of said legs, a pair of drop leaves hingedly connected to said table top at opposite sides thereof, link means interconnecting said drop leaves and said pivot rod for raising and lowering said drop leaves in unison with said table top, said drop leaves, when lowered, depending to an extent sufficient to operate as view concealing elements for said legs and the upper portions of said wheels.
